(57) **CLAIM**

The ornamental design for an electronic device connector, as shown and described.

DESCRIPTION

FIG. 1 is a front and right side perspective view of an electronic device connector showing our new design; and,

FIG. 2 is a front elevation view thereof.

The broken line portion of the figure drawings is included to show unclaimed subject matter only and forms no part of the claimed design.

1 Claim, 2 Drawing Sheets

FIG. 1

FIG. 2
